US00D904434S

(12) **United States Design Patent** (10) Patent No.: **US D904,434 S**
Chen et al. (45) Date of Patent: ** Dec. 8, 2020

(54) **ELECTRONIC DEVICE WITH GRAPHICAL USER INTERFACE**

D631,764 S 2/2011 Furetta
D640,145 S 6/2011 Goto
D640,574 S 6/2011 Giannini

(Continued)

(71) Applicant: **Apple Inc.**, Cupertino, CA (US)

(72) Inventors: **Kevin Will Chen**, Sunnyvale, CA (US);
Aurelio Guzmán, San Jose, CA (US);
Christopher I. Wilson, San Francisco,
CA (US)

FIG. 1 is a front view of a display screen or portion thereof with graphical user interface, showing the claimed design; and,

FIG. 2 is a front view of an electronic device having a display screen with the graphical user interface of FIG. 1 applied to the display screen.

The outer broken lines in the figures show a display screen or portion thereof, or an electronic device having a display screen, and form no part of the claimed design. The other broken lines in the figures show portions of the graphical user interface that form no part of the claimed design.

1 Claim, 2 Drawing Sheets
